(57) **CLAIM**

The ornamental design for a "reagent kit with multiple bottles," as shown and described.

DESCRIPTION

FIG. 1 is a front right perspective view of a reagent kit with multiple bottles.

FIG. 2 is a front view of the reagent kit of FIG. 1.

FIG. 3 is a rear view of the reagent kit of FIG. 1.

FIG. 4 is a right side view of the reagent kit of FIG. 1.

FIG. 5 is a left side view of the reagent kit of FIG. 1.

FIG. 6 is a top view of the reagent kit of FIG. 1; and,

FIG. 7 is a bottom view of the reagent kit of FIG. 1.

The features shown in broken lines form no part of the claimed design.

1 Claim, 4 Drawing Sheets
